UNITED STATES PATENT OFFICE

2,115,404

SPINNERET POLISHING MACHINE

Gerrit Spaanbroek, Asheville, N. C., assignor to
American Enka Corporation, Enka, N. C., a corporation of Delaware

Original application June 11, 1936, Serial No.
84,757. Divided and this application May 10,
1937, Serial No. 141,807

5 Claims. (Cl. 51—124)

This application is a division of my application Serial Number 84,757 filed June 11, 1936.

The present invention relates to spinnerets adapted for use in the manufacture of artificial silk, and more particularly to a machine for polishing spinnerets which have become impaired by wear or damage.

A normal spinneret as employed in the artificial silk industry is in the form of a small cup-shaped die, the base plate of which is perforated with minute openings through which a cellulosic solution may be forced as individual fine streams. It is these thus formed fine streams which when subjected to conditions to cause coagulation of the solution comprise the multiplicity of filaments used in the formation of artificial silk yarn. Due to the severe conditions to which the spinnerets are normally subjected during spinning operations, they must be constructed of materials which will withstand long and hard usage with the necessity for the replacement thereof being maintained at a minimum. The spinnerets must also be resistant to the corrosive action of the various chemicals to which they are subjected during use.

Attempts have been made to manufacture suitable spinnerets of corrosion-resistant non-metals such as glass and bakelite, but the only materials found to be generally satisfactory are the noble metals and their alloys. It is found, however, that metallic spinnerets become distorted by the pressure imposed in use and further that the minute openings in the spinnerets become clogged by incrustations and agglomerations formed from the spinning solution. Heretofore it has been the practice to melt down damaged spinnerets and to recast the metal to form spinnerets in the desired condition.

The past practice involving the reconstruction of impaired spinnerets was thought to be necessary because of the fragile character of the spinnerets and the fact that the openings therein are so minute. Reconstruction was considered essential in order that the spinnerets have the exact precision required in the production of high grade artificial silk.

This invention has as an object the provision of a device for polishing and removing a coating previously applied to spinnerets during former reconditioning stages.

It is a further object of the present invention to provide an improved polishing machine especially adaptable for polishing the faces of spinnerets that have become impaired during usage.

55 Other objects and advantages of this inven-

tion will be apparent from the following detailed description when considered in connection with the accompanying drawing wherein:

Figure 1 is a top plan view of a spinneret face-polishing mechanism; and

Figure 2 is a side elevational view of the polishing machine shown in Figure 1.

Referring to the drawing in detail, the apparatus for polishing the spinnerets is shown and includes a rigid frame-work 10 having spaced 10 upper and lower beds 11—11 inter-connected by side supports 12. The apparatus polishes the spinnerets by rotating them individually, presenting them to a rapidly rotating polishing element 13 and simultaneously oscillating the spinnerets transversely of the surface of the rotating polishing element. Said apparatus is driven from any suitable source of power (not shown) through a belt 14 which drives a pulley 16 fast to a central shaft 17 suitably journaled in upper and 15 lower beds 11. Above upper bed 11 polishing element 13 is secured to the upper end of shaft 17. Polishing element 13 consists of a circular plate 18 covered with any suitable durable polishing fabric such as canton flannel fixed to the exterior 20 right side out, and dressed with a suitable polishing medium such as chrome-oxide suspended in tallow. It will be understood that when pulley 16 is rotated circular plate 18 will be driven at 25 the same rate.

30 Rotation of the spinnerets is obtained through worm 81 on shaft 11 in driving engagement with worm wheel 82 fast to horizontal shaft 83. The shaft 83 is carried by suitable bearings 85 fixed on the lower bed 11. At one end, shaft 83 is provided with bevel gear 86 meshing with bevel gear 87 secured to rotatable vertical shaft 89 on which is fixed sprocket wheel 90. At spaced points about the polishing element 13 rotatable vertical shafts 89a, 89b and 89c are disposed, journaled in 35 suitable bearings in the beds 11. Adjacent the lower end said shafts are provided with sprocket wheels 90a, 90b and 90c respectively, which are interconnected by continuous chain 91 whereby, it will be observed rotation of bevel gear 87 40 causes shafts 89a, 89b and 89c to be driven from sprocket wheel 90.

Above the upper bed 11 the spaced vertical shafts 89, 89a, 89b and 89c are each provided with a spaced collar 93 for mounting a horizontal 50 housing or arm 94 which extends toward the axis of the polishing element 13. Horizontal arms 94 are bifurcated at each end and bored freely to accommodate at one end the vertical rotating shaft 89 and at the other a spinneret shaft 96. 55

Sprocket wheels 97, 97a, 97b and 97c keyed to the shafts 89, 89a, 89b and 89c are interconnected by chains 98 with sprockets 100 keyed to the spinneret shafts 96. Sprockets 97 and 100 have spacing hubs 101 which maintain them in horizontal alignment during polishing, the sprockets 100 being normally urged to alignment by expansion springs 102 retained thereon. Spinneret holders 103 are secured to the lower end of the shafts 96.

10 It will be observed that if the polishing plate 73 is rotated at any rate of speed the spinneret holders 103 will be driven at a corresponding but lower rate of speed through worm 81, wheel 82, shaft 83, bevel gears 86 and 87, vertical shaft 89, 15 sprocket chain 91, sprocket wheel 97, sprocket chain 98 and spinneret shafts 96.

In order to insure optimum polishing conditions and to utilize substantially the entire surface of polishing element 73, it is proposed to 20 cause the spinneret holders to traverse a constantly changing path with respect thereto, and this is accomplished by continuously oscillating horizontal arms 94 to carry the spinneret holders in an arcuate path between the axis and periphery of the polishing element. Mechanism for accomplishing this movement includes a horizontal spider 104 freely oscillatable about the main shaft 77 as an axis immediately beneath upper bed 71. Pivotal vertical rods 105 engage the under side 30 of horizontal arms 94 and extend through arcuate slots 106 formed in the upper bed 71. The projecting end of each therebeneath is fitted with a pivotally connecting link 108, the opposite end of which is pivotally connected to the under side 35 of spider arm 110. The relationship of the oscillating elements described is such that when the spider is rocked about the shaft 77 the arms 94 connected thereto by means of rods 105 and links 108 will be oscillated across the polishing element 73, the extent of said oscillation being limited by 40 arcuate slots 106.

Rocking of the spider 104 is accomplished through power derived from the belt 74 and central shaft 77, applied through the horizontal shaft 83 which carries a beveled gear 111 keyed thereto on the end opposite bevel gear 86. The bevel gear 111 engages bevel gear 112 keyed to vertical shaft 113 supported for rotation in fixed bearing 114. Secured on its upper extremity the shaft 113 is provided with disk 116 having a projecting pin 117 eccentrically disposed with respect to the shaft 113. The pin 117 rides from end to end of straight slot 118 cut in the spider 104. It will be observed that continuous rotation of 55 the shaft 113 as driven from the shaft 77 causes rotation of disk 116 to rock the spider through movement of pin 117 in opposite directions along slot 118.

Preferably the gear 112 is larger than the gear 60 87 in order that there might be obtained unbalanced equilibrium of the cooperating parts described, such coaction producing, for example, driving of the polishing disk at a speed of approximately 2,000 R. P. M. while the spinneret holders are rotated at about 100 R. P. M. and oscillated approximately 40 times per minute.

In lieu of driving the gear 112 from the shaft 83, the shaft may be connected to drive only the gear 87, it being feasible to drive the gear 112 70 directly from the main shaft 77 by connecting a suitably geared shaft between the worm 81 and the gear 112. When this modified construction is adopted, it will also enable the obtaining of different speed ratios between the cooperating 75 parts as described above in order to maintain even

distribution of wear on the polishing element. Suitable arrangements of gears and shafting, and belts and pulleys may be substituted for the chain and sprocket drive described.

Operation of these mechanisms has been found 5 to insure that all portions of the face of the spinnerets carried on the holders 103 are subjected to the uniform action of the polishing agent so that at the end of the polishing operation the face of the spinneret will have been 10 treated evenly.

It is, of course, intended that the apparatus might be operated at different relative speeds of the various movements in the practice of the invention and that the specific speeds and gear- 15 ing ratio indicated above are not essential to the successful practice of the invention.

What I claim is:

1. A polishing machine particularly adapted 20 for the polishing of spinnerets during the reconditioning thereof comprising a platform, a polishing disc above the platform fixedly supported upon a rotatably mounted shaft for rotation therewith, said shaft extending below the platform, a plurality of arms supported at their outer 25 ends upon rotatably mounted shafts with their inner ends extending over the polishing disc, a rotatably mounted spinneret holder at the inner end of each arm, a plate mounted under the platform extending adjacent each of the arms, linkage connecting the plate with respective arms, means connecting each spinneret holder with the shaft about which its respective arm is pivoted for rotating the holder upon rotation of the shaft, and means for concurrently driving the disk at a 30 high speed, the spinneret holders at a relatively low speed, through the arm supporting shafts and connecting means and for causing the arms by movement of the plate to oscillate slowly with the spinnerets mounted thereon contacting the 35 disc. 40

2. A polishing machine comprising a platform, a polishing disc above the platform fixedly supported on a rotatably mounted shaft for rotation therewith, a plurality of arms supported at their ends upon rotatably mounted shafts with 45 their inner ends extending over the polishing disc, a rotatably mounted spinneret holder at the inner end of each arm, a plate mounted under the platform extending adjacent each of the arms, linkage connecting the plate with respective arms, means connecting each spinneret holder with the shaft about which its respective arm is pivoted for rotating the holder upon rotation of the shaft, and means for concurrently driving the disc at a high speed, the spinneret holders at a relatively low speed, through the medium of the arm supporting shafts and connecting means, and for causing the arms by movement of the plate to oscillate slowly with the spinnerets mounted thereon contacting the 50 disc from immediately adjacent its center to substantially the periphery thereof, said driving means for the arms and the disc being constructed to oscillate the arms at a predetermined speed with respect to the speed of rotation of the disc, 55 such that each spinneret is contacted substantially with all portions of the disc prior to contacting the disc in a path identical to that previously traversed.

3. A polishing machine particularly adapted 70 for the polishing of spinnerets during the reconditioning thereof comprising a base and a platform spaced thereabove, a polishing disc above the platform fixedly supported upon a rotatably mounted shaft for rotation therewith, said shaft 75

extending into the space between the base and platform, a plurality of arms supported at their outer ends upon rotatably mounted shafts with their inner ends extending over the polishing disc, a rotatably mounted spinneret holder at the inner end of each arm for lightly urging a spinneret mounted thereon into contact with the disc, means connecting each spinneret holder with the shaft about which its respective arm is pivoted for rotating the holder upon rotation of the shaft, means for concurrently driving the disc at high speed, the spinneret holders at a relatively low speed, through the medium of the arm supporting shafts and connecting means and for causing the arms to oscillate slowly with the spinnerets mounted thereon contacting the disc from immediately adjacent its center to substantially the periphery thereof, said driving means for the arms and the disc being constructed to oscillate the arms at a predetermined speed with respect to the speed of rotation of the disc such that each spinneret is contacted substantially with all portions of the disc prior to contacting the disc in a path identical to that previously traversed.

4. A polishing machine particularly adapted for the polishing of spinnerets during the reconditioning thereof comprising a base and a platform spaced thereabove, a polishing disc above the platform fixedly supported upon a rotatably mounted shaft for rotation therewith, said shaft extending into the space between the base and platform, a plurality of arms supported at their outer ends upon rotatably mounted shafts with their inner ends extending over the polishing disc, a rotatably mounted spinneret holder at the inner end of each arm for lightly urging a spinneret mounted thereon into contact with the disc, a plate mounted under the platform extending adjacent each of the arms, linkage connecting the plate with respective arms, means connecting each spinneret holder with the shaft about which its respective arm is pivoted for rotating the holder upon rotation of the shaft, and means for concurrently driving the disc at a high speed, the spinneret holders at a relatively low speed, through the medium of the arm supporting shafts

and connecting means and for causing the arms by movement of the plate to oscillate slowly with the spinnerets mounted thereon contacting the disc from immediately adjacent its center to substantially the periphery thereof, said driving means for the arms and the disc being constructed to oscillate the arms at a predetermined speed with respect to the speed of rotation of the disc such that each spinneret is contacted substantially with all portions of the disc prior to contacting the disc in a path identical to that previously traversed.

5. A polishing machine particularly adapted for the polishing of spinnerets during the reconditioning thereof comprising a base and a platform spaced thereabove, a polishing disc above the platform fixedly supported upon a rotatably mounted shaft for rotation therewith, said shaft extending into the space between the base and platform, a plurality of arms supported at their outer ends upon rotatably mounted shafts with their inner ends extending over the polishing disc, a rotatably mounted spinneret holder at the inner end of each arm for lightly urging a spinneret mounted thereon into contact with the disc, a freely rotatable spider mounted under the platform and linked to each of the arms, means connecting each spinneret holder with the shaft about which its respective arm is pivoted for rotating the holder upon rotation of the shaft, and means for concurrently driving the disc at a high speed, the spinneret holders at a relatively low speed, through the medium of the arm supporting shafts and connecting means and for causing the arms by movement of the spider to oscillate slowly with the spinnerets mounted thereon contacting the disc from immediately adjacent its center to substantially the periphery thereof, said driving means for the arms and the disc being constructed to oscillate the arms at a predetermined speed with respect to the speed of rotation of the disc such that each spinneret is contacted substantially with all portions of the disc prior to contacting the disc in a path identical to that previously traversed.

GERRIT SPAANBROEK.
